MOTION PICTURE PROJECTOR

Otto R. Nemeth, Santa Monica, Calif., assignor to International Projectors, Inc., a corporation of California

Filed July 3, 1958, Ser. No. 51,644

Term of patent 14 years

(Cl. D61—1)

FIG. 1.

FIG. 2.

FIG. 3

FIG. 4.

FIG. 5.

FIG. 6.

FIG. 7.

Figure 1 is a side elevational view of a motion picture projector showing my new design;

Figure 2 is a rear elevational view thereof;

Figure 3 is a front elevational view thereof;

Figure 4 is a side elevational view thereof;

Figure 5 is a top plan view thereof;

Figure 6 is a bottom plan view thereof; and

Fig. 7 is a perspective view thereof.

The dominant features of the design are shown by the solid lines.

I claim:

The ornamental design for a motion picture projector, substantially as shown and described.
